UNITED STATES PATENT OFFICE

2,510,452

NECKTIE HANGER

William S. Witt, Cicero, Ill.

Application November 20, 1947, Serial No. 787,078

2 Claims. (Cl. 211—89)

1

My invention relates to necktie hangers of the type suspended from wall hooks and garments supporting rods, and one object is to provide a hanger of this type with means for accommodating a considerable number of neckties and holding them firmly in place.

A further object is to include a unit in the novel hanger which contains a spring clamp designed to firmly engage the necktie deposited therein.

Another object is to form the unit referred to in a manner to firmly lodge the said clamp and resist tendencies to displace it.

An important object is to design the novel necktie hanger along lines of simplicity and for easy handling.

With the above objects in view, and any others which may suggest themselves from the description to follow, a better understanding of the invention may be had by reference to the accompanying drawing, in which:

Fig. 1 is a front elevation of the hanger;

Fig. 2 is an enlarged fragment of a support contained in the hanger for necktie holding units;

Fig. 3 is a left-hand side view of the hanger; and

Fig. 4 is an enlarged section on the line 4—4 of Fig. 1.

In accordance with the foregoing, specific reference to the drawing indicates the upper portion of the hanger to be an arched bar 10 extended upwardly with an integral hook 11. The material of the parts just described may be wood, but is preferably plastic for purposes of neatness and simplicity.

The end pieces 12 of the bar 10 receive between them a bar 15 which is of the same material. The bar 15 may be secured or retained to the end pieces 12 by any suitable means, but I prefer to employ the simple expedient of a pair of pins 16 which are driven into aligned bores made in the joined parts.

The bar 15 is intended to receive a plurality of the units 18 which individually support the neckties. Generally, each unit is in the form of a figure 2, having a top hook 19 which is hung on the bar 15 for the support of the unit. The bar 15 is of square cross-section, and the fit of the hook 19 with the bar is such as to prevent vertical or lateral departure of the unit 18 from the bar. However, the unit may be swung in the manner indicated by finely dotted lines in Fig. 4 to release it from the bar.

The body of each unit 18 combines with the base 20 thereof to provide a clamping hold for

2

the necktie support by the unit. Thus, the front end of the base 20 is rounded as indicated at 22 to facilitate the easy mounting of the folded neckties. However, the advance of the necktie over the base 20 brings it into engagement by the frontal finger 23 of a spring clamp 24 carried by the unit. The back part of the clamp is in the form of a loop 25 which is frictionally lodged in a recess 26 formed between the body of the unit 18 and its base 20. Moreover, such recess is formed with a downward pocket 27 in which the loop lodges, so that it becomes firmly connected with the unit 18. It is noted that the body portion of the unit departs in a horizontal course 15 on the way to the recess 26, as indicated at 28, to create a top bearing resisting tendencies to withdraw the clamp 24 from the unit.

With the unit 18 completed as in Fig. 4, it is evident that a necktie inserted to the extent 20 shown in Fig. 3 will be firmly clamped and resist all ordinary tendencies to become dislodged or loosen from the unit. A hanger is thus provided which affords room for a considerable number of the units 18 to firmly support the neckties 25 therein. While the rod 15 is plain for general use, its smoothness may permit the units 18 to pile up toward one end of the rod when the hanger 10 is tilted. To counteract this tendency, Fig. 2 shows a modification wherein the rod 15 30 is milled or roughened on its top surface as indicated at 30. In conclusion, it may be said that the present necktie hanger is an article which may be conveniently hung over any handy nail or garment supporting rod by means of the hook 35 11 to accommodate and support a considerable number of neckties in a limited space.

While I have described the invention along specific lines, various minor changes or refinements may be made therein without departing 40 from its principle, and I reserve the right to employ all such changes and refinements as may come within the scope and spirit of the appended claims.

I claim:

45 1. The combination with a horizontal supporting bar; of a unit having a hook shaped top designed to surmount said bar, said unit having its lower portion departing at an angle to end terminating with a base, means in said angle and extending over said base for clamping a necktie inserted over the latter, said angle containing a recess continued in said base with a pocket, and said means having a loop seating in said recess and pocket and retentively secured to the unit.

50 2. A necktie supporting device comprising in

combination a horizontal square supporting bar, a hook shaped unit having a square recess on the under side of its hook portion to engage said supporting bar, said hook portion extending downwardly at an angle and terminating in a base portion, a recess formed between the junction of the hook and base portions, and a spring having a curved end mounted in said recess and extending outwardly to engage the top of the base and clamp a necktie mounted between the spring and the base.

WILLIAM S. WITT.
